DEVICE FOR SHARPENING THE BLADES OF
SLICING MACHINES FOR SLICING EAT-
ABLES

Adolf Ditting, Zurich, Switzerland

Application May 23, 1949, Serial No. 94,883
In Switzerland June 18, 1948

3 Claims. (Cl. 51—248)

1

The present invention relates to a device for sharpening the blades of slicing machines for slicing eatables.

The device is constituted by two grinding wheels set at an angle equal to the taper of the blade on a bracket provided with a means for fastening it on the carriage of the slicing machine so that to sharpen the blade the grinding wheels can be fed to the blade together with the carriage, the grinding wheel designed to remove the burr being held by a spring at a certain axial distance from the said blade so that it is only when its axle is pressed with a finger that the said grinding wheel contacts the blade in order to remove the burr produced by the grinding wheel proper.

In the accompanying drawing two embodiments of the object of the invention are illustrated by way of example.

Fig. 1 is a front view of the bracket with the grinding wheels,

Fig. 2 is a top view of Fig. 1,

Fig. 3 shows how the bracket illustrated in Fig. 1 is fastened on a V-shaped carriage,

Fig. 4 shows how the bracket illustrated in Fig. 1 is provided with a flat base and is fastened on a flat carriage.

The bracket 1 (cf. Fig. 1) has a foot 2 whose bearing surfaces 3 are inclined towards each other and correspond to the recess 4 of the V-shaped carriage 5. This V-shaped foot 2 can be slipped into the recess 4 of the carriage 5 and fastened thereon with the screw 6. The said foot can also be designed with a flat base and can, as shown in Fig. 4, be fastened on a flat carriage, for instance with thumb screws. To the foot 2 is attached an arm 7 provided with two holes which support the axles 8 and 9 of the grinding wheels 10 and 11. The angle formed by the two axles is equal to the taper of the blade 12. The wheel 10 carried by the axle 9 is pressed by the spring 13 against the collar 14 on the said axle 9. The wheel 11 carried by the axle 8 is similarly pressed by the spring 15 against the collar 16 on the said axle 8. The distance between the grinding surface of the wheel 11 and the smooth side 17 of the blade 12 is chosen so that the grinding wheel 11 does not contact the blade 12. The blade 12 is ground by the wheel 10, and the wheel 11 only serves to remove the burr produced by the wheel 10. For this purpose, on the axle 8 there is a rotatable sleeve 18 supported on a ball 19 and held fast in the other axial direction by a retaining ring 20. A light pressure of a finger on the sleeve 18 suffices to press the grinding wheel 11 against the smooth

2

side 17 of the blade 12, thus removing the burr.

In practice, if the rotary blade of the slicing machine needs to be sharpened, the following procedure is followed. Slicing machines, such as have been described, ordinarily include a movable plate substantially parallel to the plane of the blade for determining the thickness of a slice, and this plate is first moved away from the blade as far as is possible to free the edge of the blade for sharpening. The foot 2 of the grinding apparatus is then affixed to the movable carriage of the machine, as has been described, and this carriage is then moved toward the blade, which is rotating for the grinding operation. During this phase of the operation grinding wheel 11 does not contact the blade and is maintained at a fixed distance from blade 12 by spring 15. Grinding wheel 10 does come into contact with the blade edge however and, as the carriage is moved toward the blade even further, the force of the blade against wheel 10 causes the said wheel 10 to move axially outward against the force of spring 13. Thus it will be noted that the position of wheel 11 with respect to the blade is independent of carriage position, while the physical position of wheel 10 with respect to the blade varies in accordance with the relative position of blade and carriage. Inasmuch as carriage movement causes wheel 10 to move in this way when the wheel is in contact with the blade, an automatic pressure control is effected during the grinding operation.

The burr which is formed by the abrasive action of wheel 10 on the rotary blade is removed by manually pressing wheel 11, against the action of spring 15, into contact with the blade edge.

I claim:

1. A device for sharpening the blades of slicing machines having a carriage for carrying the article to be sliced and a rotatable blade for slicing said article, comprising a single supporting arm having an integral pedestal removably mounted upon said carriage, said supporting arm defining first and second bores the axes of which form an angle equal to the taper angle of the edge of said blade, first and second axles passing respectively through said bores and axially movable therein, a first abrasive disc carried by said first axle adjacent one face of said blade edge, said first axle including first spring biasing means urging said first disc into contact with said one face, and a second abrasive disc carried by said second axle adjacent the other face of said blade edge, said second axle

including second spring biasing means normally maintaining said second disc away from said other face, said second axle also including a sleeve attached thereto whereby said second axle may be moved in said second bore against the action of said second spring biasing means to place said second abrasive disc in contact with said other face of said blade edge at the will of the operator, said rotatable blade being mounted substantially perpendicularly to the direction of travel of said carriage, said first axle being movable in said first bore against the action of said first spring biasing means as said carriage is moved toward said rotatable blade whereby said first abrasive disc is maintained in contact with said one face of said blade and the physical position of said first abrasive disc with respect to said supporting arm varies with the position of said moving carriage, the position of said second abrasive disc with respect to said supporting arm being independent of the position of said moving carriage.

2. The device of claim 1 wherein said supporting arm is substantially perpendicular to the direction of travel of said carriage, said pedestal being formed at one extremity of said supporting arm and including a bore receiving screw means for removably fastening said pedestal to said

carriage, one of said first and second bores being adjacent the other extremity of said supporting arm, and the other of said first and second bores being intermediate the extremities of said supporting arm.

3. The device of claim 2 wherein said first and second axles include collars between said abrasive discs and said supporting arm to determine limit positions of said abrasive discs.
